BY

Tomally
ATTORNEY

UNITED STATES PATENT OFFICE.

OTTO G. MOLL, OF DETROIT, MICHIGAN.

COMBINATION PRIMER, FUEL ECONOMIZER, AND HUMIDIFIER.

Application filed January 16, 1926. Serial No. 81,672.

My invention relates to a new and useful improvement in a combination primer, fuel economizer and humidifier adapted for use in internal combustion engines. One of the objects of the invention is the provision of a device of this class which may be quickly and easily attached on a vehicle having an internal combustion engine for propelling the same.

10 Another object of the invention is the provision of a mechanism of this class whereby a volume of combustible fuel may be delivered directly to the combustion chamber for priming purposes, through a simple and easy operation of the mechanism.

Another object of the invention is the provision of a device of this class whereby a quantity of air and water mixed together to form a moist vapor may be delivered to the 20 internal combustion engine with a resultant saving in fuel and an increase in operating efficiency.

Another object is the provision of a device of this class whereby the nature of the fuel 25 delivered to the combustion chamber may be controlled so that an easy and smooth running motor is effected.

Other objects will appear hereinafter.

The invention consists in the combination 30 and arrangement of parts hereinafter described and claimed.

The invention will be best understood from a reference to the accompanying drawings which form a part of this specification and in which

35 Fig. 1 is a vertical central sectional view of the mechanism taken on substantially line 1—1 of Fig. 3.

Fig. 2 is a sectional view taken on substantially line 2—2 of Fig. 1.

40 Fig. 3 is a front elevational view of the plate and mechanism mounted upon and projecting through the supporting body.

As shown in the drawings there is mounted 45 upon the dash 9 of the vehicle with which used an instrument plate 10 having graduations 11 formed thereon and other indicating matter to indicate the direction of turning of the various operating mechanism. Positioned in 50 an opening 12 formed in the dash 9 is a tubular member 13 which is projected through an opening formed in the plate 10 and provided with a lock nut 14 engaging the outer surface of the plate 10 and with a lock nut 15 engaging 55 the inner surface of the dash 9. Threaded upon the tubular member 13 is a housing 16 in

which is threaded the threaded portion 17 of the priming rod 18, which projects through the cap 19 threaded on the outer end of the tubular member 13, this cap 19 having an air 60 relief opening 20 formed therein. Mounted upon the outer end of the rod 18 is a knob or hand-hold 21. Positioned upon the rod 18 is a sleeve 22 having at one end a head 23. Mounted upon the sleeve 22 is a plunger guide 65 and spacer 24. Positioned between the plunger guide and spacer 24 and the sleeve head 23 is a leather cup 25. Threaded on the sleeve 22 is a nut 26 which serves to bind against the plunger guide and spacer 24 a 70 leather cup 27. This nut 26 serving to bind the leather cup 25 against the head 23 so as to clamp it between the head 23 and the plunger guide or spacer 24. Pins 28 and 29 are projected through the rod 18 to properly locate 75 the position of the sleeve 22 thereon. The construction is such that when the threaded portion 17 is disengaged from the threads of the housing 16 the rod 18 may be used for pumping purposes, the tubular member 13 80 forming the cylinder and the leather cups forming the piston. It is evident that on the retractive movement of the piston the air will be forced outwardly from the opening 20 which is formed in the cap 19, and that this 85 opening 20 will permit the entry of air into the cylinder upon movement of the piston in the opposite direction.

A seat 30 is formed in the housing for receiving the end of the rod 18 which is formed 90 to provide a needle valve. A passageway 31 leads from the seat 30 and connects with the opening formed in the seat forming bushing 32 which is threaded into the plug 33, which is screwed into the housing 16. Connected 95 to the plug 33 is a delivery pipe 34 which connects with a T 35 projecting outwardly from which is a pipe 36 carrying on its end a nozzle 37 having a plurality of emission passages 38 and 38' formed therein. It will be noted that 100 the outlet of these emission passages are extended in different directions. Connected to the T 35 is another pipe 39 which connects to the L 40 projecting from which is the pipe 41 carrying a nozzle 42 constructed similar to 105 the nozzle 37. It is believed evident that any number of nozzles may be used as desired, these nozzles being projected in any suitable manner into the intake manifold of the engine between the engine and the carburetor. 110 The chamber 43 which is formed in the housing 16 communicates through the passage 44

with the chamber 45 formed in the plug 46 which is threaded into the housing 16. This plug 46 communicates by means of the passage 47 with a pipe 48 connected to a T 49 which communicates by the pipes 50 and 51 with the source of fuel supply. Positioned in the chamber 45 is a ball 52 which in one position serves as a closure for the passage 46 so as to prevent communication of this passage 46 with the chamber 45. A pin 53 is projected across the chamber 45 so as to prevent the ball 52 from closing the end of the passage 44. Projected across the chamber 33' which is formed in the plug 33 is a pin 54, to prevent the ball 55 which is positioned in the chamber 33' from closing the communication between the chamber 33' and the pipe 34. The ball 55 is intended to engage the bushing 32 so as to close communication between the cylinder forming tubular member and the pipe 34. Mounted in the housing 46 is a cock plug 56 having a passage 57 formed therein so that when the cock plug is turned by means of the rod 58 which carries the indicating or operating handle 59, to the position shown in Fig. 1 the chamber 43 will be in communication with the source of fuel supply. It is evident that upon retracting the piston in the tubular member 13 the ball 55 will move to position so as to close communication between the tubular member 13 and the delivery pipe 34, while at the same time the ball 44 will be lifted from its seat to permit communication between the cylinder forming tubular member and the source of fuel supply, thus permitting the piston to draw into the tubular member 13 a supply of fuel. Upon movement of the piston in the opposite direction the ball 44 will serve to close communication between the cylinder 13 and the source of fuel supply and the ball 55 will move from its seat to permit the passage of the fuel from the cylinder 13 to the nozzles 37 and 42. In this way a quick and easy priming of the engine is effected.

An extension 58' is formed on the housing 46, this extension being connected to the housing 46 by a neck 59 through which projects a passage 60 communicating with the passage 57 by the passage 61 formed in the cock plug 56. Formed in the neck 60 and communicating with the passage 59 is a passage 62 which communicates with the atmosphere and permits the entry of air into the passage 60 and thence through the passage 57 into the delivery pipe 34, by way of the cylinder 13. It will be noted from Fig. 2 that the cock plug 56 may be rotated so that the air may be drawn into the pipe 34 at the same time that water is drawn therein and that at the will of the operator the gas alone may be drawn into the cylinder 13.

Positioned in the extension 58 is a cock plug 63 which is operated by the rod 64 carrying the operating handle 65. This extension 58

communicates by the nipple 66 with a suitable source of water supply, so that upon opening of the cock plug 63 the water supply may be brought into communication with the passage 57 and drawn into the engine.

In operation after the priming has been effected the rod 18 may be threaded into the housing 16 so that it remains stationary. The hand hold or indicator 59 is then moved to the position so as to close the connection between the delivery pipe 34 and the source of fuel supply. This will be effected by turning the stop cock plug 56 as shown in Fig. 2 in a clockwise direction through ninety degrees. This will leave the delivery pipe 34 in condition for communication with the air supply passage 62 and if desired, upon a proper rotation of the cock plug 63, with the source of water supply so that the engine will draw into the intake manifold a mixture of air and water. When it is desired to draw into the intake manifold air only the cock plug 63 will be turned so as to shut off the supply of water. When used in this manner the device operates as a fuel economizer supplying a larger amount of air to the fuel mixture and thus thinning it out with the consequent saving results in the consumption of fuel.

The water control may be moved so as to permit the entry of water in small degrees, as by a drop at a time. Such an arrangement will humidify the fuel mixture and afford an easy and speedy running motor giving the same effect as is ordinarily produced in a motor when driven in the night time or in a damp atmosphere. Upon admission of a larger amount of water by proper regulation of the cock plug 63 the water admitted to the combustion chambers may be used as a carbon remover, the exploding gases in the combustion chambers serving to raise the temperature of the water sufficiently to generate steam.

The structure of the device is a simple and compact one which affords economy in manufacture while at the same time the durability and efficiency of such a device is maintained.

While I have illustrated and described the preferred form of structure, I do not wish to limit myself to the precise form of structure shown, but desire to avail myself of such variations and modifications as come within the scope of the appended claim.

Having thus described my invention what I claim as new and desire to secure by Letters Patent is:

In a device of the class described adapted for use on internal combustion engines having an intake manifold, comprising: ejector nozzles communicating with said manifold; a delivery pipe communicating at one end with said nozzles; a head connected to said delivery pipe at the opposite end, said head having a plurality of passages formed therein in communication with said delivery pipe; a cylinder communicating with said passages; a piston

slidably mounted in said cylinder; a piston rod connected to said piston and extending at one end exteriorly of said cylinder and projecting beyond said piston at the opposite end, said 5 opposite end being tapered to form a needle valve, a portion of said opposite end intermediate said piston and said needle valve forming portion being threaded into said head; a water conduit connected to a suitable source of 10 water supply and communicating with passages in said head; a fuel conduit connected to a suitable source of fuel supply and communi-

cating with said passages in said head, said head having an air passage communicating with the atmosphere, the needle valve forming portion of said rod being adapted, upon a threading of said rod in said head, for controlling communication of said delivery pipe with said sources of fuel, and water supply and the air. 15

In testimony whereof, I have signed the foregoing.

OTTO G. MOLL.
